UNITED STATES PATENT OFFICE.

EDWARD M. BARNES, OF HASTINGS, MICHIGAN, ASSIGNOR TO ADVANCE M'F'G. CO., OF HASTINGS, MICHIGAN, A CORPORATION OF MICHIGAN.

ELECTRIC MOTOR.

1,034,408.

Specification of Letters Patent.

Patented Aug. 6, 1912.

Original application filed June 17, 1911, Serial No. 633,642. Divided and this application filed October 14, 1911. Serial No. 654,575.

To all whom it may concern:

Be it known that I, EDWARD M. BARNES, a citizen of the United States, residing at Hastings, Michigan, have invented certain new and useful Improvements in Electric Motors, of which the following is a specification.

This invention relates to improvements in electric motors.

10 My improvements relate particularly to the casing for electric motors, which is adapted to provide an effective mounting for the parts of the motor.

15 My improved motor is especially designed by me for use on carpet sweepers, and I here show the same as applied to a carpet sweeper, such as is shown in my application for Letters Patent filed June 17th, 1911, Ser. No. 633,642, this application being 20 a division thereof.

The main objects of this invention are to provide an improved motor casing which may be formed of sheet metal, in which the parts are very simple and economical to produce and assemble, and afford an effective support for the motor parts, as well as a casing therefor.

25 Further objects, and objects relating to structural details, will definitely appear 30 from the detailed description to follow.

I accomplish the objects of my invention by the devices and means described in the following specification.

The invention is clearly defined and 35 pointed out in the claims.

A structure which is a preferred embodiment of my invention, is clearly illustrated in the accompanying drawing, forming a part of this specification, in which:

40 Figure I is a detail perspective view of a vacuum cleaner structure embodying the features of my invention. Fig. II is an enlarged detail view, partially in vertical section, on a line corresponding to line 2—2 of Fig. I. Fig. III is a horizontal section taken on a line corresponding to line 3—3 of Fig. II, parts being shown in full lines.

45 Fig. IV is a detail vertical section taken on a line corresponding to line 4—4 of Fig. III, the bolt 10 being shown in full lines. Fig. 50 V is a detail vertical section of a slightly modified structure, showing the casing adapted for general application.

In the drawings, similar reference characters refer to similar parts throughout the several views, and the sectional views are taken looking in the direction of the little arrows at the ends of the section lines.

Referring to the drawing, the fan casing 1 of the vacuum cleaner structure illustrated 60 is mounted upon the shoe 2. As the structural details and features of this shoe and fan casing form no part of my present invention, I do not describe the same with further detail herein.

65 The motor casing consists of a section 3, which, in the structure illustrated, is mounted upon the fan or driven member casing 1, and a top or outer section 4 mounted on the section 3. Both of these motor casing 70 sections 3 and 4 are sheet metal stampings. The motor casing section 3 is provided at its inner end with an outturned flange 5, which rests upon and is secured to the driven member casing 1 by bolts or rivets 75 not here illustrated. At its outer end, the section 3 is shouldered at 6 to receive the outer section 4, and is provided with an in-turned flange 7. This flange 7 is provided with ears 8, on which the fields 9 of the 80 motor are mounted by means of the bolts 10, the fields being arranged under the flange, as is clearly shown in the drawings. The flange 7 is provided with upwardly-projecting brackets or arms 11, in which the brush 85 holders 12 are mounted. The fields and brushes are thus securely supported and maintained in their proper relation to the other parts of the motor. I do not describe the structural details of these fields, as they 90 form no part of my present invention.

The upper end of the motor shaft 13 is supported by the bearing 14 carried by the casing section 4, the casing section being provided with an inwardly-projecting bearing supporting flange 15, into which the bearing is forced, the bearing having a flange 16 at its outer end.

100 The brushes 17 coact with the commutator 18 on the motor shaft. The tubular brush holders 12 are provided with tubular insulating sleeves 19 arranged through suitable flanged openings in the arms 11. The brushes 17 are slidably mounted in the holders and yieldingly supported therein by 105 means of the springs 20, the inner ends of

the springs engaging the brushes, while the outer ends of the springs engage the plugs 21 threaded into the holders.

The motor casing section 4 is provided with openings 22 through which the brushes may be inserted or removed. The section 4 also has ventilating openings 23. The bearing 24 for the inner end of the motor shaft is supported on the driven member casing 1, 10 the casing being provided with a flange opening 25 for the bearing, which has a flange 26 at its outer end similar to that on the bearing 15.

The fan 27, which is the driven member 15 in the structure illustrated, is arranged upon the end of the shaft and secured by suitable nuts. An oil conduit 28 extends from the casing wall to the bearing 24. The outer bearing is lubricated from the end.

20 With the parts of the casing thus formed and arranged, the parts of the motor are incased and protected, and effectively supported so that they are kept in alinement and no additional brackets or supporting 25 means are required. The casing is very economical to produce and is easily assembled and owing to the form of the parts or sections thereof, can be made of very light material and is still very strong and rigid.

30 In Fig. V, I show a casing modified for general purposes, the casing section 3' being shouldered at its lower end to receive the section 29, which is drawn in at its inner end to close the end of the casing. The bearing 24 is mounted in the casing section 35 29.

Other modifications will no doubt suggest themselves to those skilled in the art to which my invention relates.

40 I have illustrated and described my improvements in Figs. I to IV in the form in which I have embodied the same in manufacturing for the market. I have not attempted to illustrate or describe all the various modifications which I conceive to be possible, as they will, as stated, no doubt be obvious to those skilled in the art, but I desire to be understood as claiming the same specifically, as illustrated, as well as broadly 45 within the scope of the appended claims.

Having thus described my invention, what I claim as new and desire to secure by Letters Patent is:

1. The combination of a driven member 55 casing; a cylindrical motor casing formed of sheet metal mounted on said driven member casing and consisting of an inner section having an out-turned flange at its inner end secured to said driven member casing, and an inturned flange at its outer end, said inturned flange being provided with upwardly-projecting arms and inwardly-projecting ears, and an outer section sleeved upon said inner section, said 60 inner section being shouldered to receive 65

70 said outer section; a motor comprising a shaft, a commutator, an armature, and field magnets, said field magnets being arranged under said flange at the outer end of said inner section and secured to the inwardly-projecting ears thereof; brush holders mounted on said arms on said flange; and bearings for said shaft, the inner bearing being mounted on the said driven member casing and the outer bearing on said outer section of said motor casing.

2. The combination with a driven member casing; a cylindrical motor casing formed of sheet metal mounted on said driven member casing and consisting of an inner section having an inturned flange at its outer end, said inturned flange being provided with upwardly-projecting arms and inwardly-projecting ears, and an outer section sleeved upon said inner section; a motor comprising a shaft, a commutator, an armature, and field magnets, said field magnets being arranged under said flange at the outer end of said bottom section and secured to the inwardly-projecting ears thereof; brush holders mounted on said arms on said flange; and bearings for said shaft, the inner bearing being mounted on the said driven member casing and the outer bearing on said outer section of said motor 95 casing.

3. The combination with a driven member casing, of a cylindrical motor casing formed of sheet metal mounted on the said driven member casing and comprising an inner section having an out-turned flange at its inner end secured on said driven member casing, and an inturned flange at its outer end, and an outer section sleeved upon said inner section; a motor comprising a shaft, a commutator, an armature and field magnets, said field magnets being mounted on said flange at the outer end of said inner section; brush holders mounted on said flange; and bearings for said shaft, the inner bearing being mounted on said driven member casing and the outer bearing on said outer motor casing section.

4. The combination of a driven member casing; a motor casing formed of sheet metal mounted on said driven member casing and comprising an inner section having an inturned flange at its upper end, and an outer section sleeved upon said inner section; a motor comprising a shaft, a commutator, an armature, and field magnets, said field magnets being mounted on said flange at the outer end of said inner section; brush holders mounted on said flange; and bearings for said shaft, the inner bearing being mounted on said driven member casing and the outer bearing on said outer motor casing section.

5. The combination of a cylindrical motor casing formed of sheet metal and comprising an inner section having an out-

turned flange at its inner end, and an inner turned flange at its outer end, and an outer section sleeved upon said section; a member to which said inner flange of said inner section is secured; and a motor comprising field magnets, said field magnets being mounted on said flange at the outer end of said inner section.

6. The combination of a cylindrical motor 10 casing formed of sheet metal consisting of a section having an inturned flange at one end, said flange being provided with laterally-projecting arms and inwardly-projecting ears, and a second section sleeved upon said 15 flanged section, said flanged section being shouldered to receive said second section; a motor comprising a shaft, a commutator, an armature, and field magnets, said field magnets being arranged against said flange and 20 secured to the inwardly-projecting ears thereof; brush holders mounted on said arms on said flange; and a bearing for said shaft mounted on the said second section of said casing.

25 7. The combination of a cylindrical motor casing formed of sheet metal consisting of a section having an inturned flange at one end, said flange being provided with laterally-projecting arms and inwardly-projecting ears, and a second section sleeved upon 30 said flanged section, said flanged section being shouldered to receive said second section; a motor comprising a commutator, an armature, and field magnets, said field magnets being arranged against said flange and 35 secured to the inwardly-projecting ears thereof; and brush holders mounted on said arms on said flange.

8. The combination of a cylindrical motor 40 casing formed of sheet metal consisting of a bottom section having an inturned flange at its inner end, said flange being provided with laterally-projecting arms, and a second section sleeved upon said flange 45 section; a motor comprising a shaft, a commutator, an armature, and field magnets, said field magnets being secured to said flange; brush holders mounted on said arms on said flange; and a bearing for said shaft

mounted on the said second section of said 50 casing.

9. The combination of a cylindrical motor casing formed of sheet metal consisting of a bottom section having an inturned flange provided with laterally-projecting arms; 55 and a second section sleeved upon said flanged section; a motor comprising a shaft, a commutator, an armature and field magnets, said field magnets being secured to said flange; and brush holders on said arms on 60 said flange.

10. The combination of a motor casing formed of sheet metal and comprising a section having an inturned flange at one end, and a second section sleeved upon said 65 flanged section; and a motor comprising field magnets, said field magnets being mounted on said flange on said motor casing section.

11. The combination with a motor, of a 70 cylindrical sheet metal motor casing comprising a pair of sections, the one section being provided with an inturned flange at one end and being shouldered to receive the other casing section, the other casing section being cup-shaped and inverted thereon; and a 75 motor shaft bearing mounted on the other section of said motor casing, the motor field and magnets and brushes being mounted on said inturned flange of said motor casing. 80

12. The combination with a motor, of a cylindrical sheet metal motor casing comprising a pair of sections, one section being provided with an inturned flange at one end, the other section being cup-shaped and inverted thereon; and a motor shaft bearing mounted on the second section of said motor 85 casing, the motor field magnets being mounted on said flange of said motor casing section. 90

In witness whereof, I have hereunto set my hand and seal in the presence of two witnesses.

EDWARD M. BARNES. [L. s.]
